Fig. 1

To all whom it may concern:

Be it known that I, Charles U. Deaton, a citizen of the United States, residing at Kirkwood, in the county of St. Louis and State of Missouri, have invented a new, original, and ornamental Design for a Vault Closure Unit, of which the following is a specification, reference being had to the accompanying drawing, forming part thereof.

Fig. 1 is a front elevational view of a vault closure unit showing my new design, the door being shown in the closed position in the door opening of the door frame.

Fig. 2 is a vertical sectional view thereof, as on line 2—2, Fig. 1, looking in the direction of the arrows.

Fig. 3 is a view similar to Fig. 1, the door being shown in the open position swung out of the door opening of the door frame, and the day gate being shown in the closed position in the inner end of the vestibule.

Fig. 4 is a vertical sectional view thereof, as on line 4—4, Fig. 3, looking in the direction of the arrows.

I claim:

The ornamental design for a vault closure unit substantially as shown and described.
